[57] CLAIM

The ornamental design for an electrical connector housing, as shown and described.

DESCRIPTION

FIG. 1 is a top plan view of an electrical connector housing showing our new design;

FIG. 2 is a front elevational view thereof;

FIG. 3 is a bottom plan view thereof;

FIG. 4 is a left side elevational view thereof;

FIG. 5 is a right side elevational view thereof;

FIG. 6 is a rear elevational view thereof;

FIG. 7 is a perspective view thereof, looking from front side;

FIG. 8 is a perspective view thereof, looking from rear side;

FIG. 9 is a perspective view thereof, looking from the rear side where the terminal holder is removed for the purpose of a complete disclosure; and

FIG. 10 is a perspective view thereof, aligned with a mating connector housing. The mating connector shown in broken lines is included for illustrative purposes only and forms no part of the claimed design.
